UNITED STATES PATENT OFFICE.

JOHN J. OLSON, OF BELVIEW, MINNESOTA.

DERRICK.

1,314,357.

Specification of Letters Patent. Patented Aug. 26, 1919.

Application filed January 11, 1918. Serial No. 211,405.

To all whom it may concern:

Be it known that I, JOHN J. OLSON, a citizen of the United States of America, residing at Belview, in the county of Redwood and State of Minnesota, have invented new and useful Improvements in Derricks, of which the following is a specification.

The invention relates to an improvement in a form of derrick to be used for hoisting one end of automobiles, wagons or the like, so that a full view underneath may be had thereof.

Its principal object is to provide a device of this character by means of which either the front or rear end of a vehicle may be raised quickly and effectively.

A further object is the provision of a device of this character which may be readily folded into a compact bundle when not in use.

A still further object is to provide a device of this character which may be easily and cheaply made and which will be simple in construction and operation.

Other and further objects will appear as a detail description of the device progresses.

To the exact construction shown in the drawings, the invention is not to be restricted. The right is reserved to make such changes or alterations as an actual reduction to practice may suggest, provided such changes or alterations do not deviate from the spirit of the subjoined claims.

In the accompanying drawings:

Figure 1 is a side elevation of the invention, showing it in use as a means for raising the rear end of an automobile.

Fig. 2 is a perspective view of the tripod.

Fig. 3 is a perspective view of the vehicle supporting frame.

Fig. 4 is a vertical sectional view through the apex of the tripod and one of the legs thereof.

Fig. 5 is a detail sectional view through the plate connecting the legs of the vehicle supporting frame.

Fig. 6 is a detail sectional view showing the manner in which the attendant sections of the supporting braces for the legs of the tripod and the legs for the vehicle supporting frame are held together.

Referring to the drawings, there is shown a tripod A and a vehicle supporting frame B. The tripod A comprises a crown piece 1 having the shape of a frustum of a trihedral pyramid and legs 2 which are pivotally connected to this crown piece. The crown piece

1 has formed on each of its three sides slots 3 which open at the bottom of the crown piece and in these slots the upper ends of the legs 2 are attached by pivotal engagement with the pins 4 which are positioned transversely in the slots and are fixed to the walls thereof on opposite sides of the slots. The pins 4 are fixed at substantially the middle 65 of the slots with reference to the length and depth of the latter. Below the point where the pins are carried the slots are made deeper than at higher points, so that the legs 2 may be moved in toward the center of 70 the crown piece. To preclude movement of the legs away from the crown piece farther than a specified distance, the slots 3 are so formed that the ends of the legs above the pins 4 may abut the bottoms of the slots. 75

Each of the legs 2 is provided on its bottom end with a caster 5 that is suitably attached thereto and the three legs are connected near their lower ends by sectional braces 6. Each of these sectional braces 6 80 comprises a section 7 and a section 8 which are pivotally connected together by means of a stud 9. The free ends of the two sections 7 and 8 connect one to each of any two adjacent legs 2, the connections with the legs 85 being pivotal and effected by means of the studs 10 which loosely engage the ends of the sections but which are fixed in the legs. The section 8 overlaps the section 7 beyond a point where it effects pivotal engagement 90 with the latter and the end of this overlapping portion receives a thumb screw 11 which threads through it and sinks its conical end 12 in a counter-sunk conical depression formed in the section 7. The purpose 95 of this screw 11 is to effect a rigid connection between the sections 7 and 8 when it is so desired, the withdrawing of the screw from the conical depression referred to permitting the sections to be moved with reference to each other on the pivotal connection 9.

On the bottom face of the crown piece 1 a screw eye 13 is suitably attached by threaded engagement in the center of the 105 crown piece. The purpose of this screw eye is to support the block and tackle 14, the free end of the tackle passing down one of the legs 2 and winding on a rotatably mounted drum 15 provided with ratchet teeth 16 and 110 a crank handle 17. A pawl 18 is loosely swung from the leg 2 just below the ratchet teeth and is designed to engage the latter and prevent the drum from such movement

as will tend to unwind the end of the tackle carried thereon.

Coöperating with the tripod A there is a vehicle supporting frame B. This frame comprises a plate 19 and the attendant legs 20 which are pivotally connected to the plate. In plan the plate 19 has the shape of an isosceles trapezoid and the legs 20 are attached thereto on the longer base, being held in slots 21 formed in this longer base of the trapezoid and supported on pins 22 near the ends of the slots. The slots 21 are so formed that the legs 20 may be moved toward each other but are limited to a distance which they may be moved away from each other, the ends of the slots wherein the legs are attached being inclined, so that the legs may lie against these inclined ends at the same angle of inclination with respect to the parallel sides of the plate 19 that the inclined sides of the plate have with respect to these parallel sides. An eye 23 is formed transversely in the plate 19 at the longitudinal center of the latter and at the opposite side from that in which the slots 21 are formed. This eye is designed to be engaged by a hook 24 carried by the block and tackle so that the plate may be raised for a purpose yet to be described. The free end of each leg 20 terminates in a curved portion 25 which lies in a plane at right angles with the plate 19. Just back of these curved portions 25 the two legs are joined together by a brace 26 which, with the exception of its longitudinal dimension, is identical with the braces 6. Between the brace 26 and the plate 19, each leg 20 is provided with a hook member 27 which is suitably attached to either leg. Both these hook members are designed to engage the axle of the automobile or other vehicle being raised for inspection on the bottom.

A consideration of Fig. 1 makes the operation of the device apparent. When the frame B is placed below a vehicle and its hooks 27 are made to engage behind the axle thereof, this frame may be raised at that end having the plate 19, because of the block and tackle engaging this end and being raised by means of the drum 15 which is turned by the crank handle 17. This operation, of course, raises that axle of the vehicle which the hooks 27 engage and, as the frame B is being raised, the casters 10 permit the tripod A to roll in, so that the eye 23 in the plate 19 may remain always directly below the center of the tripod. The ends of the frame B have no casters and their frictional engagement with the ground preclude any longitudinal movement of this frame. Raising the end having the plate 19 though, causes this end to describe an arc and the casters on the tripod A permit the

tripod to roll in to accommodate for this. Were this provision not made, the raising of the frame B would move this end to one side of the center of the tripod and might result in the overturning of the latter. As long as the pawl 18 remains in connection with one of the ratchet teeth of the drum 15 any vehicle that is so raised with the device will remain suspended for inspection. The removal of the pawl from the teeth will permit the reverse operation of the drum and the lowering of the frame B. 75

When the device is not in use it may be easily folded up, the particular method of construction making provision for this. The disengaging of the screws 11 of the section 8 from the conical-shaped depression 80 in the section 7 will permit the braces 6 to be folded on themselves and the pivotal mountings on the legs 2 will permit their being folded against each other with the folding up of the braces. By this means, 85 the tripod A is collapsed and the vehicle supporting frame B is collapsed in the same way by the folding up of its brace 26 which is identical in construction with the braces 6. The frame B and tripod A may 90 then be formed into a compact bundle for transportation to other points or for storage.

The invention having been described, what is claimed as new and useful is: 95

1. In a device as set forth, a hoisting apparatus, and a vehicle supporting frame, the latter comprising a plate, legs pivotally connected to the plate, the legs being formed with curved ends whose extremities lie substantially in planes at right angles to the legs, the legs diverging from the plate, a jointed brace interconnecting the legs adjacent their diverging ends, and vehicle axle engaging members carried by the legs at 105 intermediate points for the useful purpose specified.

2. In a vehicle hoist, a hoisting frame, casters on which the said hoisting frame is carried, a vehicle supporting frame having 110 axle engaging means and ground engaging ends, and hoisting means carried by the hoisting frame and engaging the remaining end of the vehicle supporting frame, whereby the said end of the said frame may be elevated to hoist one end of a vehicle, the casters on the hoisting frame permitting the latter to move as the said end of the vehicle supporting frame is raised to keep such end below the center of the hoisting frame without movement of the ground engaging end of the vehicle supporting frame with respect to the ground. 115 120

In testimony whereof I affix my signature.

JOHN J. OLSON.
